DRAINBOARD

Kent C. Haven, Syracuse, N. Y., assignor to Easy
Washing Machine Corporation, Syracuse, N. Y.,
a corporation of Delaware

Application April 1, 1937, Serial No. 134,350

3 Claims. (Cl. 210—75)

My invention relates to new and useful improvements in drainboards for laundering machines and relates more particularly to a drain or drip board adapted to be used with a clothes drier or a drainboard to be used in connection with that type of washing machine in which an extractor or clothes drying apparatus is mounted on a common base with a washing machine.

In clothes washing and drying machines of the type wherein a pair of vats are employed, one for containing elements for washing the clothes and the other for containing mechanism for drying the clothes, the washing and extractor vats are usually mounted in juxtaposition upon a common base. To prevent drippage of the cleansing fluid on the floor as the clothes are transferred from the washing vat to the extractor vat, it has been customary to utilize some form of drainboard between the washing vat and the extractor vat adapted to cause such drippage to drain back into the washing vat.

In addition to preventing drippage of fluid on to the floor as the clothes are transferred from the washer to the extractor, it is desirable to provide means for preventing drippage as the clothes are transferred from an external vessel, such as a laundry tray, to the extractor or from the extractor to the external vessel. Several methods have been employed to accomplish both of these objects. One of the most common is to provide two fixed drainboards one on each side of the extractor. Another is to provide a single drainboard rotatable to various circumferential positions with respect to the extractor. A third method is to provide a fixed drainboard between the extractor and washer and utilize the under surface of the cover of the extractor as a second drainboard. Each of these methods required rather cumbersome, expensive apparatus or apparatus which is not very convenient to operate.

An object of my invention is to provide an inexpensive drainboard structure which is easy to operate and which is adapted to accomplish the purposes outlined above.

A further object of my invention is to provide a combined cover and drainboard structure which, when in one of its positions, acts as a cover for the extractor and, when in the other of its positions, provides two drainboard surfaces to prevent drippage of fluid on to the floor either when the clothes are being transferred from the washing vat to the extractor or from the extractor to an external vessel.

More specifically, my invention contemplates the provision of a frame member at the top of the

extractor vat adapted to carry a two-part cover which, when closed, serves as a cover for the extractor vat and which, when open, has one half extending between the extractor and the washing vat and the other half extending outwardly from the extractor vat from another side to thus provide two drainboard surfaces on opposite sides of the extractor vat.

Other objects and advantages of my invention will be more apparent from the following description when taken in connection with the accompanying drawing, in which:

Figure 1 is a fragmentary vertical view indicating a washing vat and an extractor vat with my novel drainboard structure mounted thereon.

Figure 2 is a top plan view showing my novel drainboard structure with one-half of the cover in an open drainboard position.

Figure 3 is a view taken on the line 3—3 of Figure 2.

Figure 4 is a view taken on the line 4—4 of Figure 2.

Although my novel drainboard structure, generally indicated by the numeral 11, is adapted to be used with an extractor mounted separately from a washing machine, it has been shown in use on an extractor vat 12 which is mounted in juxtaposition to a washing vat 13 containing the usual means for washing clothes. It will be understood that the extractor vat 12 and the washing vat 13 are mounted on a common base supported by legs as shown, for example, in Nelson Patent No. 2,007,112, filed December 8, 1932, and issued July 2, 1935. The extractor vat 12 has mounted therein any suitable means for drying clothes, such as a rotatable perforated basket 15, which, since it does not constitute a part of my present invention, need not be more particularly described. The washing and drying mechanism may be driven by any suitable means and may be driven either separately or from a common motor.

To receive the combined drainboard and cover structure 11, the upper end of the extractor vat 12 is bent outward, as indicated at 14, and the upper circular edge thereof is provided with a U-shaped annular rubber ring. A frame member 17 has a downwardly depending annular flange 18 adapted to be wedged inside of the U-shaped ring 16 to thereby retain the combined cover and drainboard structure 11 in position on top of the extractor vat 12. A plurality of tie rods 20 extending between the base (not shown) and the frame serve to hold the structure rigidly in assembled condition. An opening marked by the

depending flange 18 is provided in the frame member to enable access to the rotatable basket 15 for convenient insertion or removal of clothes.

The frame member 17 has a shelf portion 19 extending completely around the top of the extractor which may, if desired, be slightly inclined toward the extractor in all directions. Fluid dripping on to this portion of the drainboard structure will flow into the extractor vat 10 over the annular flange 18 and into the space 21 around the rotatable basket and thence into the bottom of the extractor vat to be pumped back into the washer vat or into an external vessel as is common practice in the art to which this invention applies. At the outer edge of the frame member an upwardly extending flange 22 is formed which completely encircles the frame member. The flange is decreased in height along the straight edges 24 to form rests for cover members 26 and 27 when they are in an open position. The encircling flange prevents fluid on the flat surface 19 from dripping on the floor.

The cover members 26 and 27 are hinged, at 28 and 29 respectively, to the upwardly extending flange 22 of the frame member. A pair of rubber bumpers 31, secured to the frame member, cushion the fall of the cover members when they are thrown to a closed position. Rubber bumpers 32, one carried by each of the cover 30 members, engage the portions 24 of the flange and serve to cushion the fall of the cover members when they are thrown to an open position. The cover members are each provided with a handle 33 by which they may be conveniently 35 raised or lowered.

On its under surface, at each of the side margins thereof, each of the cover members 26 and 27 is provided with a downwardly extending flange 36 which, when the cover members 40 are open, as indicated in Figures 2 and 3, serve to confine and direct the flow of liquid which may drip on to the drainboard surfaces.

It will be particularly noted, as shown in Figure 3, that when the cover members are open 45 the drainboard surfaces extend downwardly away from the extractor so that the liquid is shed away from the extractor. The cover and drainboard structure described is inexpensive to build as all the parts thereof are metal stampings which may be quickly and readily assembled. Moreover, the structure provides not only a cover for the extractor which is pleasing in appearance, but a pair of drainboards on opposite sides of the extractor which are the most 50 used drainboard positions, one between the washing vat and the extractor and the other between the extractor and an external vessel, such as a laundry tray, not shown.

It will be apparent that I have provided a 55 novel combined cover and drainboard structure

for the clothes drying extractor of a laundering machine and that various modifications and changes in the form and relation of parts thereof may be made without departing from the spirit of my invention as set forth in the appended claims.

I claim:

1. In a combined clothes washing and drying machine of the class wherein a washing vat and an extractor vat having openings at the upper ends thereof are mounted side by side upon a common base, an apertured frame member mounted on the extractor vat independently of the washing vat with the aperture thereof in registration with the opening in said extractor vat, said frame having a shelf portion surrounding the aperture thereof and extending outwardly therefrom in a substantially horizontal plane above the washing vat, a pair of closure members hinged to the frame member at opposite sides thereof to swing from a closed position over said aperture to an open position extending in opposite directions from said aperture over and beyond corresponding side portions of the frame shelf, said closure members being so constructed and arranged that when in the closed position they constitute a complete cover for the frame aperture and extractor vat opening and when in the open position they constitute downwardly inclined drainboards, one of said members being arranged to extend when in the open position over the washing vat in registration with the opening thereof.

2. In a device of the class described, a vat having an opening at the upper end thereof, a frame member mounted on the vat and having a shelf portion surrounding said opening and extending outwardly therefrom in substantially a horizontal plane, a pair of closure members hinged to the frame member at opposite sides thereof to swing from a closed position over the vat opening to an open position extending in opposite directions from said opening over and beyond corresponding side portions of the frame shelf, said closure members being of such a character that when in the closed position they constitute a complete cover for the extractor vat opening and when in the open position they constitute downwardly inclined drainboards, said frame being provided with an upwardly extending marginal drip flange completely surrounding the shelf portion thereof.

3. A device as defined in claim 2 wherein a portion of the drip flange extending beneath the closure members when in the open position is of less height than the remaining portion thereof and forms rests for the closure members when said members are in their open position.
